Patented Aug. 6, 1918.

UNITED STATES PATENT OFFICE.

JOSEPH BLUHM, OF TROY, NEW YORK, ASSIGNOR TO THE DANA MANUFACTURING CORPORATION, OF TROY, NEW YORK, A CORPORATION OF NEW YORK.

DESIGN FOR AN ICE-CREAM SPOON, DISHER, OR SIMILAR DEVICE.

52,250.

Specification for Design.

Patented Aug. 6, 1918.

Application filed March 14, 1916. Serial No. 84,232. Term of patent 14 years.

To all whom it may concern:

Be it known that I, JOSEPH BLUHM, a citizen of the United States, residing at Troy, in the county of Rensselaer and State of New York, have invented a new, original, and ornamental Design for an Ice-Cream Spoon, Dish, or Similar Device, of which the following is a specification, reference being had to the accompanying drawing, forming part thereof.

Figure 1 of the drawing is a bottom plan view of an ice-cream spoon having a handle embodying my design.

Fig. 2 is a view in side elevation of the same.

Copies of this patent may be obtained for five cents each, by addressing the "Commissioner of Patents, Washington, D. C."

The design resides particularly in the handle-portion of the device, and I do not claim the bowl of the spoon as part of my design, as I contemplate placing the design upon other articles than that particularly shown in the drawing.

I claim:

The ornamental design for an ice-cream spoon, dish, or similar device, substantially as shown.

JOSEPH BLUHM.
